UNITED STATES PATENT OFFICE.

WILLIAM L. WILLIAMSON, OF COLLINS, MISSISSIPPI.

FLUE-SUPPORT.

No. 851,720.

Specification of Letters Patent.

Patented April 30, 1907.

Application filed October 2, 1905. Serial No. 281,067.

To all whom it may concern:

Be it known that I, WILLIAM L. WILLIAMSON, a citizen of the United States, residing at Collins, in the county of Covington, State of Mississippi, have invented certain new and useful Improvements in Flue-Supports; and I do hereby declare the following to be a full, clear, and exact description of the invention, such as will enable others skilled in the art to which it appertains to make and use the same.

This invention relates to that class of flue supports particularly designed for use in the ceiling of a room, to hold the flue from contact with the rafters between which it passes, and at the same time to form a support for the chimney.

The particular object of the invention is not so much to provide an article capable of performing new functions, as it is to provide one that can be manufactured at a minimum cost out of scrap iron or steel, thus eliminating the necessity of patterns and the expensive process of malleable casting which would be necessary in an article of this kind if of cast iron.

The present invention is therefore essentially a new article of manufacture, for the reason that its advantages are directed more particularly to facilitate and cheapen the manufacture than to effect the use of the article.

In the drawings: Figure 1 is a top plan view of the invention. Fig. 2 is a side elevation of the structure shown in Fig. 1. Fig. 3 is a sectional view showing a modification.

Referring now to the drawings, the present hanger comprises two U-shaped straps each including a web portion 2, and sides 3 and 4, the end portions of the sides being bent outwardly at right angles in a common plane, as illustrated at 5 and 6.

In the structures shown, Figs. 1 and 2 of the drawings, additional straps 9 and 10 are disposed upon the web portions 2 directly

adjacent to the sides 3 and 4 so that they lie in spaced relation, and they are held secure in place by bolts 11.

In use, the support is disposed with its outwardly turned end portions 5 and 6 upon rafters 7 and 8, between which the web portions 2 and the straps 9 and 10 lie, and outline a frame through which the smoke pipe is received. The flue or chimney, as may be used, is disposed or built upon the webs 2 and the straps 9 and 10 so that the several parts are held as supported securely in their proper positions.

Instead of fastening the straps 9 and 10 to the webs 2 by means of bolts 11, said straps, as illustrated at 9' in Fig. 3, have their extremities bent downwardly as illustrated at 9^a to lie against the outer edges of the webs of the U-shaped strap and hold the straps 9' against longitudinal displacement, it being understood that the weight of the flue or chimney will hold the straps 9' against any upward movement while lateral movement toward each other will be prevented by the smoke pipe which is received between them.

What I claim is:

As an article of manufacture, a flue support consisting of two parallel spaced U-shaped metal straps having their extremities turned outwardly at right angles in a common plane, and a pair of independently formed parallel spaced cross-straps, disposed upon the web portions of the U-shaped straps and having their ends turned downwardly against the outer edges of the webs of the U-shaped straps, whereby longitudinal displacement of said cross-straps from said U-shaped straps is prevented.

In testimony whereof, I affix my signature, in presence of two witnesses.

WILLIAM L. WILLIAMSON.
